UNITED STATES PATENT OFFICE.

DANIEL F. SULLIVAN, OF LOWELL, MASSACHUSETTS, ASSIGNOR TO DANIEL J. MURPHY, OF SAME PLACE.

KNITTING-MACHINE.

SPECIFICATION forming part of Letters Patent No. 629,880, dated August 1, 1899.

Application filed April 28, 1898. Serial No. 679,070. (No model.)

To all whom it may concern:

Be it known that I, DANIEL F. SULLIVAN, a citizen of the United States, residing at Lowell, in the county of Middlesex and Commonwealth of Massachusetts, have invented a certain new and useful Improvement in Knitting-Machines, of which the following is a specification.

My invention relates to knitting-machines of that kind which are circular and adapted to knit one or more courses of a yarn of one color and then one or more courses of a yarn of another color; and it consists in the devices and combinations hereinafter described and claimed for changing automatically from one color to another.

This invention is an improvement on the knitting-machine shown and described in the patent to Michael J. Dinneen, dated November 26, 1889, and numbered 415,834, and while using some of the parts shown in that machine differs therefrom mainly in employing a pattern-cylinder instead of a flexible pattern-tape, in cutting the yarn by drawing a knife across the same instead of breaking the yarn or cutting the yarn by pressing it against the sharpened nibs of the loop-wheel, and in operating the fluted feed-rolls not continuously, but only when a new yarn is being introduced into the machine.

In the accompanying drawings, Figure 1 is a plan of my improvement with such parts of a circular-knitting machine as are necessary to the understanding of said improvement; Fig. 2, a side elevation of said improvement; Fig. 3, an inner end elevation of the same, omitting the pattern-cylinder; Fig. 4, a plan of the same, omitting a part of the pattern-cylinder and the top plate; Fig. 5, a vertical longitudinal section on the line 5 in Fig. 3; Fig. 6, a cross-section on the line 6 in Fig. 5; Fig. 7, a plan of the cam carried by the needle-cylinder, with a part of said cylinder, omitting the needles.

The needle-cylinder A, needles a, needle-clamps a', and loop-wheel B are of the usual construction and operation and are used with other parts commonly used in circular-knitting machines.

On a suitable stand C on a vertical screw or stud c turns the pattern-cylinder D, pro-

vided with ratchet-teeth d, adapted to be engaged by a pawl E, pivoted on the pawl-lever e. The fulcrum of the pawl-lever is concentric with the pattern-cylinder, and the pawl E is held in engagement with the teeth d by a spring, represented as a spiral spring e', stretched between a pin e², which extends down from the free end of said pawl, and a screw-eye e³, inserted in said lever e.

On a vertical stud e⁴, adjustably secured in an obvious manner in a slot e⁵ in the end of pawl-lever nearest the loop-wheel, turns an antifriction-roll e⁶, which once in every revolution of the needle-cylinder is struck by a cam a², which may be and is represented as being substantially like the cam marked by the same letter of reference in said Dinneen patent. When the cam a² passes the free end of the pawl-lever, the pattern-cylinder is caused to rotate an angular distance represented by one of the teeth d.

The pattern-cylinder may be prevented from turning too far by friction in any usual manner, as by a leather washer inserted between the washer c', which surrounds the screw c², and the pattern-cylinder.

The other operative parts of my invention are supported directly or indirectly upon an arm F, rigidly secured to the stand C or other immovable object. The top plate G is pivoted at g, at the end nearest the pattern-cylinder, between ears f' f² on said arm F and serves as a yarn-guide, having as many yarn-eyes g' g² or holes as there are yarns y y', the drawings representing the device as intended for two yarns. From the usual spools or bobbins (not shown) the yarns pass separately through the yarn-eyes g' g² and together through another eye g³ in a vertical yarn-plate g⁴, rigidly secured on said top plate. The top plate is raised on its pivot g to enable the yarn to be passed through the yarn-eyes g' g² g³, but in operation is held down upon the arm F by a latch H, which engages notches f³ f⁴ on opposite sides of vertical studs f⁵ f⁶, rigidly secured in said arm F at opposite sides of said top plate. Said latch H is preferably a piece of thin or sheet metal having two turned-up portions or vertical ears h h', arranged diagonally opposite each other, by pressing which ears in opposite di-

rections, as by the thumb and a finger of the same hand, said latch may be turned in either direction, with a pivot h^2 , Fig. 5, secured to the under side of said latch and entering a hole g^5 in the top of the top plate G.

The horizontal fluted feed-rolls I I' are constructed substantially like those shown in said patent, the upper one I being journaled in the top plate and being lifted therewith when the yarns are being threaded into the machine, and the lower feed-roll I' being journaled in the bottom plate G', which is pivoted to the arm F at g^6 between flanges $f^7 f^8$ on said arm and is lifted toward the roll I by a spring g^7 , acting on said bottom plate, as shown in Fig. 5. The depth to which the flutes of the rolls I I' engage each other is limited by an adjustable stop represented as a screw g^8 , which turns in said bottom plate and strikes against the under side of the arm F. When the rolls I I' are in engagement and the knitting-machine is in operation, said rolls are turned by a yarn running between them from the yarn-plate g^4 to the loop-wheel B.

In a groove f^9 in the top of the arm F are guided longitudinally two yarn-clamps J J', the ends of said clamps nearest the pattern-cylinder being halved together at $j^1 j^2$, so as to lap each other laterally, as shown in Figs. 4 and 5, while the other ends of said clamps are arranged side by side. The overlapping ends of said clamps are beveled at $j^2 j^3$ to allow the pattern-studs $d^1 d^2$ of the pattern-cylinder to slip easily past them as said pattern-cylinder is turned, and said beveled ends are held in engagement with said pattern-studs by the expansion of spiral springs j^4 , arranged in longitudinal holes j^5 in the ends of said clamps and pushing rods j^6 against the yarn-plate g^4 and reacting on said clamps. Each clamp is provided with a clamping-rod j^7 , having an enlarged head j^8 , which is pressed slightly toward the yarn-plate g^4 by a spring j^9 , arranged in a hole j^{10} above and parallel with the hole j^5 , so that when said clamp is pushed toward the yarn-plate by a pattern-stud (d^1 or d^2) a yarn is clamped between said plate and the head j^8 , the yarns in passing from the eyes $g^1 g^2$ to the eye g^3 in the yarn-plate passing directly across the path of said heads j^8 , as indicated in Fig. 6.

The pattern-studs $d^1 d^2$ are preferably screws, which enter holes $d^3 d^4$ in the pattern-cylinder, Figs. 1, 2, and 4, there being as many annular rows of these holes as there are yarn-clamps and as many holes in each row as there are ratchet-teeth d , the holes in the upper row being each preferably immediately over a hole in the lower row. Each pattern-stud moves the clamp in the same plane therewith to cause the yarn which corresponds to said clamp to be held against the yarn-plate during one course of knitting or one revolution of the needle-cylinder and prevents said yarn from reaching the loop-wheel, so that if all the holes in both rows of

the pattern-cylinder were filled with pattern-studs no yarn would enter the machine, and if all the studs were removed both yarns would enter the fabric.

To make a horizontally-striped fabric, it is necessary that only one yarn should be introduced at a time. Therefore wherever a pattern-stud is inserted the pattern-hole immediately above or below it is left empty, and in order that the yarn for the next stripe may be drawn by the yarn of the stripe just being completed a pattern-stud is omitted from each row of holes at the proper point to allow both clamps to be out of contact with their yarns at the time the change is being made.

When both clamps are out of contact with their yarns, the feed-rolls are in engagement with each other and are revolved by the unbroken yarn being drawn between them by the action of the loop-wheel and needles, and said feed-rolls will feed in the other yarn if the latter reaches through the yarn-plate far enough to be caught between said feed-rolls. When either clamp is thrown toward the yarn-plate by a pattern-stud, as above described, a cam-shaped projection j^{11} on the under side of such clamp rides up on an incline g^9 , with which the top of the bottom plate is provided, and throws the lower feed-roll I' out of engagement with the upper feed-roll I and both feed-rolls stop, the yarn running below and out of contact with the upper feed-roll I, except when said yarn is raised by the rising of the lower feed-roll. By this arrangement the stationary yarn is not worn out or broken or accidentally drawn into the machine by the action of said feed-rolls. Of course a yarn held by a clamp, as above described, will, if the machine be running, be broken somewhere between the clamp and the loop-wheel, but at what place is very uncertain, and the break may occur so near the clamp that the broken yarn will not be caught by the unbroken yarn or by the feed-rolls and carried to the loop-wheel.

I cut the yarn at the proper time by means of a swinging knife K, which may consist of a piece of sheet-steel, pivoted at k on the top plate G near the pivoted end of said top plate and extending over the latch H (and incidentally retaining said latch on said top plate) and beyond the other or free end of said top plate, where said knife is bent vertically downward at k' in front of, but out of contact with, said top plate and the bottom of the downhanging portion being rounded and sharpened at k^4 . The shank or horizontal portion of the knife is provided with inclined shoulders $k^2 k^3$ on opposite sides thereof, and pins $g^{10} g^{11}$, which are secured vertically in ears $g^{12} g^{13}$ on the clamps J J', project up through slots $g^{14} g^{15}$ on opposite sides of said shank, so that when a clamp is moved outward by a pattern-stud the pin on said clamp strikes a shoulder on the shank of said knife and throws its curved edge against

the yarns, which at that time are both running into the loop-wheel and needles together, and cuts the clamped yarn, while the loose unclamped yarn is not cut, but yields under the curved lower edge of the knife, allowing the knife to pass over it. The groove f^9 is widened to permit the movement of the ears $g^{12} g^{13}$, as shown in Fig. 4. The cutting of the old yarn takes place as soon as the new yarn is caught by the loop-wheel.

5 The yarn end to be introduced lies between the feed-rolls and reaches to the place on the yarn-table L where it was left by the last previous cutting, and as soon as the corresponding clamp releases said yarn end it is carried by the combined action of the feed-rolls and the friction of the old or uncut yarn running through the same eye g^4 to said loop-wheel, the antifriction-roll e^6 then being upon 15 the rest a^5 of the cam a^2 and the pattern-cylinder having been turned by the action of the first cam-surface a^3 sufficiently to partially close the previously-open clamp and partially open the previously-closed clamp. 25 The remaining movements of the clamps and the above-described action of the knife, which immediately follows the completion of said clamp movements, are effected by the action of the greater cam-surface a^4 of the cam a^2 .

30 I claim as my invention—

1. The combination of a pivoted knife, having shoulders, a stationary yarn-plate, having a single yarn-delivery eye, yarn-clamps, having projections to strike said shoulders, to turn said knife upon its pivot and to move its cutting edge in the direction of the length of said edge, and adapted to clamp yarn against said yarn-plate, a needle-cylinder and needles, carried by said cylinder.

40 2. The combination of a pivoted knife, having shoulders, a stationary yarn-plate, having

a single yarn-delivery eye, yarn-clamps, having projections to strike said shoulders, to turn said knife upon its pivot and to move its cutting edge in the direction of the length 45 of said edge, and adapted to clamp yarns against said yarn-plate, a loop-wheel, a needle-cylinder and needles, carried by said cylinder.

3. The combination of a pair of feed-rolls, 50 one of said rolls having fixed bearings, a yielding bearing supporting the other of said rolls, clamps, each adapted to clamp a yarn against a fixed surface, and means for permitting said rolls to engage each other when all of said 55 clamps are open and of holding said rolls out of engagement when any of said clamps is closed.

4. The combination of a rotary needle-cylinder, the pattern-cylinder, pattern-studs, secured therein and projecting therefrom, means of rotating said pattern-cylinder an equal angular distance at each revolution of said cylinder, sliding clamps, spring devices to move said clamps toward said pattern-cylinder, a stationary surface, against which said clamps are forced by said pattern-studs, and a pair of feed-rolls, one of said rolls having fixed bearings, a yielding bearing, supporting the other of said rolls and provided with 65 an incline, each of said clamps being provided with a cam-shaped projection, adapted to ride on said incline when said clamp is moved toward said stationary surface.

In witness whereof I have signed this specification, in the presence of two attesting witnesses, this 23d day of April, A. D. 1898.

DANIEL F. SULLIVAN.
